IMPROVEMENT IN LAMP-BURNERS.

JOHN F. SANFORD, OF KEOKUK, IOWA.

Letters Patent No. 60,263, dated December 4, 1866.

SPECIFICATION.

TO ALL WHOM IT MAY CONCERN:

Be it known that I, JOHN F. SANFORD, of Keokuk, in the county of Lee, and State of Iowa, have invented an Improvement in Lamp-Burners; and I do hereby declare that the following is a full, clear, and exact description thereof, reference being had to the accompanying drawings, making a part of this specification, in which—

Figure 1 is a view of one side of the burner.

Figure 2 is a view of the upper movable section of the burner, showing a door on the side of the same.

Figures 3 and 4 are views showing the wick-adjusting spurs in two positions.

Figure 5 is a top view of the burner with the cone removed.

Figure 6 is a section through the upper section of the burner, taken in the horizontal plane indicated by red line $z z$ in fig. 2.

Figure 7 is a perspective view of the wick-spur bearing.

Similar letters of reference indicate corresponding parts in the several figures.

This invention consists in providing for removing the wick-adjusting spurs from a lamp-burner at pleasure, for the purpose of sharpening them when their points become so dull as to act imperfectly upon the wick; said spurs being supported, when in the burner, upon bearings which are adjustable, and by means of which the wick-spurs can be set nearer to the wick, as may be desired, for the purpose of keeping the spurs in good working order for a great length of time, as will be hereinafter described.

The invention also consists in applying a pivoted valve or door to the outside of the burner-case for covering an opening which is made through said case for the purpose of receiving through it a lighted taper for lighting the wick without removing the chimney; said valve being acted upon by a spring for holding it in place over its opening, and so arranged as to be operated or closed by an upward and downward or vertical pressure, as will be hereinafter described.

To enable others skilled in the art to understand my invention, I will describe its construction and operation.

Externally, the lamp-burner may be made of the same shapes as the well-known burners which have been in common use before my invention. The body of the burner consists of two sections, A and B, which are horizontally divided, and connected together by a pin and thumb-screw, as shown in the drawings, figs. 3 and 4, or in any other suitable manner, which will admit of the removal of the perforated section B from the tube-holding section A at pleasure. The upper section, B, is provided with a thumb-screw, a , for holding the chimney in place, also with a cone, C, as shown in figs. 1, 3, and 4. The wick-tube b is secured to the bottom of the lower section, A, and to the lower part of this wick-tube a thin metal plate, c , is suitably secured, which projects upward nearly to the top of the burner, and on that side thereof which is opposite the adjusting-spurs for raising and lowering the wick. This plate, c , is constructed with two bearings, c^1 c^2 , for the stem, d , of the wick-spurs, e . The bearing, c^1 , is perforated for receiving the inner end of the stem d , and the bearing c^2 is made in the form of a hook, as shown in figs. 5 and 7, for the purpose of allowing of the removal of the stem d with its spurs when the upper section B is detached from the lower section. There is an oblong notch made in the upper edge of the lower section, A, coinciding with the openings through the bearings c^1 c^2 for the purpose of receiving through it the stem d so that one end of this stem will project outside of the burner, as shown in figs. 1 and 5. A thumb-screw, e^1 , is tapped through the upper end of the plate c and bears against the wick-tube, as shown in figs. 3 and 4. By means of this screw the axis of the stem d can be adjusted nearer to or set further from the wick-tube, as may be required. The plate c may be made of spring metal and so applied to the wick-tube that the upper end of this plate will press against the upper end of the wick-tube when it is not resisted and held out by the screw e^1 . This will keep the stem d steady and cause the spurs e to be held firmly in contact with the wick. An opening is made through the side of the wick-tube in the usual manner, for allowing the spurs e to impinge upon the wick and to move the latter when the stem d is turned. It has been found that the points of the spurs e will in a very short time become so dull that they will cease to operate perfectly upon the wicks in the tubes. When this occurs the section B is removed and the spurs e taken out and sharpened. When these spurs are returned to their place in the burner they are adjusted up to the wick by the set-screw e^1 , so as to compensate for the difference in diameter of the spurs after they are sharpened, by bringing their axes nearer to the wick. In this way the spurs e can be kept sharp and in good working order as long as the body of the burner serves its purpose.

Hitherto the wick-adjusting spurs have been applied permanently to the burners, and could not be conveniently removed, for which reason the burners are thrown aside as useless when the spurs cease to operate well.

An opening, *h*, is made through the upper section, *B*, for the purpose of receiving through it a lighted taper or lighting the wick without removing the chimney. This opening is closed, when the lamp is lighted, by means of a perforated valve, *g*, the extension of which is pivoted to the burner section *A*, as shown in figs. 2 and 6, so is to be opened and closed by a vertical pressure. A lip, *i*, is struck up from the section *A* so as to impinge upon the edge of the valve *g*, when this valve is closed, and keep it in place.

I am aware that it is not new to have "lighting" holes through the burners of the lamps, nor is it new to close such holes by means of laterally movable slides, and therefore I do not claim such an arrangement as my invention. It will be seen that the valve *g* is so applied to the burner that there will be no danger, from upsetting a lamp, in opening and closing it, as the pressure is applied in a vertical instead of a lateral or horizontal pressure.

What I claim as new, and desire to secure by Letters Patent, is—

The application of a wick-spur stem, *d*, to adjustable bearings in such manner that this stem, with its spurs, can be removed from the burner at pleasure, substantially as described.

2. Constructing the body of the burner of two sections, *A* *B*, in combination with wick-spurs, which are so applied that they can be detached from their bearings, *c¹* *c²*, at pleasure, substantially as described.

Witness my hand, the matter of my application for a patent for improvement in lamp-burners.

JNO. F. SANFORD.
